UNITED STATES PATENT OFFICE.

WILLIAM H. DOWE, OF NEW YORK, N. Y., ASSIGNOR TO CINCHA STOPPER COMPANY, A CORPORATION OF MAINE.

BOTTLE-STOPPER.

No. 831,331.

Specification of Letters Patent.

Patented Sept. 18, 1906.

Application filed April 30, 1906. Serial No. 314,426.

To all whom it may concern:

Be it known that I, WILLIAM H. DOWE, a citizen of the United States, residing at the city of New York, in the borough of Brooklyn, and State of New York, have invented certain new and useful Improvements in Bottle-Stoppers, of which the following is a full, clear, and exact description.

My invention relates to bottle caps or stoppers, particularly to that class in which the cap is normally held to the bottle by cam or other means and is removable or replaceable whenever desired.

The principal object of the present invention is to facilitate the assembling of the various parts when the cap is manufactured.

With this and other objects in view the invention consists in the form and arrangement of the cam-slot, as hereinafter set forth and shown, and finally particularly pointed out in the appended claims.

In the drawings, Figure 1 is a side view of the bottle-cap embodying the principles of my invention. Fig. 2 is a similar view showing the cam in position to be assembled upon the other parts. Fig. 3 is a detail sectional view of the clamping-handle, showing its relation to the wire clamping-ring when being assembled thereupon.

In assembling the parts of the Kirkegaard stopper hitherto used, and particularly the form in which the cam-slot has both of its walls curved and constituting the cam-surfaces, a great deal of difficulty has been found in placing the cam upon the wire ring. For the purpose of assembling the parts more quickly, with greater facility and more cheaply, I have devised a construction in which the cam is capable of performing all of the functions that it had hitherto and at the same time may be assembled upon the wire ring by a simple movement, so that the trouble and expense of this part of the process is almost wholly eliminated.

The improvement consists, broadly stated, in enlarging the lower end of the cam-slot to such a size that it will receive one of the hooks at the end of the wire ring by a simple sidewise movement and without any difficult manipulation.

Referring to the drawings, 1 indicates a bottle-cap having depending fingers 2 and a wire ring 3, the ends 4 of which are bent around to form hooks. 5 denotes the cam,

having a curved slot 6 and a handle 7. The 55 cam is perforated at 8 to fit upon one of the hooks 4.

Instead of making the lower end of the curved slot 6 terminate abruptly, as in the usual form, I continue the slot to a point beyond its normal working portion and form an enlargement at the terminal end, as shown at 9. The enlargement is preferably elongated in a direction passing through the pivot-point 8. The amount of such elongation corresponds to the amount that the hooks 4 are bent around or turned over.

The use and operation of the invention are as follows:

The caps are formed with the wire rings 70 assembled therein by a special machine, and the cams are likewise produced in quantities with the slot 6 punched out therein to the proper shape. It is then merely necessary to assemble the cam 5 with its perforation 8 upon one of the hooks 4, the relation at this time being clearly shown in Fig. 3. In this process the cam is held so far tilted up that the elongated hole 9 comes opposite the other hook 4. In this relation the direction of 80 elongation of the hole 9 corresponds to the length of the hook 4, so that the cam slips over the hook by a simple sidewise movement. The handle 7 is then depressed, which causes the cam-slot 6 to move downward 85 on its hook 4 until the ring and fingers 2 arrive at their normal or untensioned state. This condition corresponds to a middle position of the cam-slot 6 upon its hook, so that there is no liability of the hook to ever reën- 90 ter the elongated hole or extremity 9 of the slot. The corners 10 of the slot at the point of its junction with the elongated hole 9 are, however, rounded, so as not to impede the reëntrance of the hook into the slot in any 95 case should the hook be accidentally displaced into the elongated hole.

Whenever the cap is used, it is placed on a bottle and the cam-lever 7 pushed downward until the cam-slot 6 has tightened the hooks 200 4 enough to clamp the cap in place. In removing the cap the reverse movement takes place; but the cam is not forced upward to such an extent that the hook 4 reënters the hole or enlargement 9.

What I claim is—

1. In a bottle-cap having depending fingers and a clamping-ring with hooks thereon,

a cam having a curved slot of substantially uniform width throughout its middle portion to engage one of said hooks, and having an enlargement at the end of said slot to facilitate the assembling of the cam upon the ring.

2. In a bottle-cap having depending fingers and a clamping-ring with hooks thereon, a cam having a curved slot of substantially uniform width throughout its middle portion and a perforation respectively adapted to receive said hooks, the extremity of said slot being enlarged to form an elongated hole, as and for the purpose set forth.

3. In a bottle-cap having depending fingers and a clamping-ring with hooks thereon, a cam having a curved slot and a perforation adapted to receive said hooks, said curved slot being formed to receive its hook at about the middle portion of the slot when the ring and fingers are in their untensioned state, and said slot having an enlargement at its

lower extremity to form a hole, the width of which corresponds to the length of said hooks.

4. In a bottle-cap having depending fingers and a clamping-ring with hooks thereon, a cam having a curved slot and a perforation respectively adapted to receive said hooks, said slot being formed to receive its hook at about its middle portion in the normal or untensioned state of said ring and fingers, and said slot being formed at its lower extremity with an elongated enlargement having rounded corners at its junction with said slot, the elongation or said enlargement lying in a direction toward said perforation, as and for the purpose set forth.

In witness whereof I subscribe my signature in the presence of two witnesses.

WILLIAM H. DOWE.
